HEEL PRESSING MACHINE

William C. Card, Jr., Winthrop, Mass., assignor
to Compo Shoe Machinery Corporation, New
York, N. Y., a corporation of Delaware

Application July 23, 1935, Serial No. 32,692

17 Claims. (Cl. 12—125)

This invention relates generally to heel pressing operations in the manufacture of shoes, and more particularly to the cement affixation of heels to lasted shoes.

5 An object of the invention is to provide a heel affixing or pressing machine having an improved construction capable of giving enhanced performance.

More particularly, objects of the invention are 10 to provide a machine for pressing heels to shoes, which is easy to operate and is rapid and efficient in production.

Another object of the invention is to provide 15 an improved method of attaching and treating heels.

Other objects of the invention will in part be obvious and will in part appear hereinafter.

The invention accordingly comprises the features of construction, combination of elements, 20 and arrangement of parts, which will be exemplified in the construction hereinafter set forth and the scope of the application of which will be indicated in the claims.

For a fuller understanding of the nature and 25 objects of the invention, reference should be had to the following detailed description taken in connection with the accompanying drawings, in which:

Fig. 1 is a side elevation of a heel pressing machine embodying principles of the invention, parts 30 thereof being broken away and shown in section better to illustrate the construction;

Fig. 2 is a fragmentary vertical sectional view, 35 on an enlarged scale, showing one of the presses used in the machine;

Fig. 3 is a fragmentary vertical sectional view taken substantially along line 3—3 of Fig. 2; and

Fig. 4 is a fragmentary vertical sectional view taken substantially along line 4—4 of Fig. 3.

40 The machine of the present invention is generally useful in any operation involving the pressing of heels against the heel seat of a lasted shoe. It is specifically intended for the cement affixation of high heels to ladies' and misses' 45 shoes, although it will be understood that its principles and features of construction are applicable regardless of the particular type of footwear involved, and also whether the affixation is effected entirely by means of cement, or whether 50 nailing, screwing or other forms of fastening means are employed, so long as it is desired to apply pressure against a heel located in position on the heel seat of a shoe.

Referring more particularly to the drawings, 55 there is a frame 10 which is adapted to be set or

fastened on the work room floor. This frame has a vertically extending bearing 11, serving as the axis for a horizontally rotatable table 12 which preferably rests on a suitable ball bearing race 13. The bearing 11 is hollow and extends upwardly above the table and to this upwardly extending portion is fixedly clamped a hollow column 14 having a cantilever arm 15 extending upwardly and outwardly therefrom. Pressure applying means in the form of a fluid pressure cylinder 16 is mounted on the outer end of such arm. A piston 17 is located in such cylinder and has a downwardly extending rod 18 which is adapted to apply pressure to a press ram 19 locatable therebeneath, which will be more particularly described hereinafter.

The piston 17 is adapted to be operated by a suitable pressure fluid, such as compressed air, and to this end the cylinder is provided with a conduit 20 for applying downward pressure and 20 a conduit 21 for applying upward pressure. These conduits are led into a suitable control valve unit generally designated 22. A foot treadle 23 controls this valve unit, being capable in one position of communicating a source 24 of pressure 25 fluid with conduit 20, while venting conduit 21, and in another position of communicating conduit 20 with the source 24 while venting conduit 20. In this latter position, air entering conduit 21 positively forces the piston 17 upwardly and at 30 the same time forcibly expels compressed air through the conduit 20. This expelled air is preferably connected within the valve unit to a conduit 25 terminating in a nozzle 26 which is directed toward and located in the vicinity of 35 the lower portion of one of the heel presses other than that located at the loading station about to be described. This expelled air is adapted to blow dust from the press toward which it is directed into a dustbin 27 located on an arm 28 which is 40 attached to the frame 10. Such dust is caused by rasping operations on the heel breast, etc., which are preferably carried out while the shoes are still in the machine, prior to affixing the breast flap to the heel breast. Thus, in a preferred use of the machine about to be described in detail, a heel is clamped to the heel seat of a shoe in one of the presses at a loading station and the machine is then rotated to bring such press and its clamped shoe to a rasping station, where 50 suitable smoothing operations such as rasping the heel breast joint are effected by means of conventional or suitable rasping equipment (not shown). Cement may also be applied to the heel breast flap and/or to the heel breast at this rasping 55

- ing station, or at a succeeding station, as desired, and the press is moved further to a breast flap sticking station where the breast flap is rolled or clamped against the heel breast while the shoe and heel are still under pressure in the clamp. Any suitable or conventional rolling or clamping device may be used for this step. The shoe may then be taken from the press machine, after the heel cement has set, and after the breast flap is located against and stuck to the heel breast.
- A plurality of presses are mounted about the margin of the table, the number of presses being sufficient to permit cemented work in any given press to set during a traverse between loading and unloading positions. Each press comprises a base 29, which is rotatably mounted on a pivot 30 attached to the table 12. A spring pressed detent 31 is adapted to register with a depression in the surface of the table so as to tend to hold each press in the normal position shown in Fig. 1, while permitting turning of the press with respect to the table in order to facilitate handling of the work, as during loading, rasping, burnishing, breast flap laying, and like operations.
- The press base 29 is provided with a slideable carriage 32, which is confined for sliding movement in guideways 33. A tiltable jack pin holder 34 is adjustably fixed in carriage 32 by means of a pin 35 which may be selectively inserted in different sets of registering openings 36 and 37 through the carriage and pin holder respectively. As will be apparent from an inspection of Fig. 3, the pin holder may thus be mounted in different tilted positions with respect to the carriage to provide for different types of lasts. A last jack pin 38 is carried by the pin holder and is adapted to have the pin hole or thimble in the cone of a last seated thereover.
- The under side of carriage 32 has a rack 39 affixed thereto in mesh with a pinion 40 keyed for rotation with a shaft 41 which is journaled in the base 29. The outer end of this shaft has keyed thereto a control handle 42, equipped with an internal plunger 43 (Fig. 4) which abuts against one end of a spring pressed dog 44, that rides over a toothed plate 45 affixed to the press base. As will be apparent from the drawings, depression of plunger 43 enables the operator to turn the handle 42 so as to slide the carriage in its guides, while the release of the plunger enables the spring for the dog 44 to urge the latter into locking relation with the teeth of plate 45 so as to hold the carriage in any chosen position.
- A standard 46 extends upwardly from press base 29 and is bowed thereover so as to present a hollow ram journal 47, located at its upper end, substantially directly over the pivot 30. The ram 19 is slidably mounted in such journal and is given a normal spring bias upwardly by means of a compression spring 48, which acts between the journal 47 and a head 49 on the ram. A seat member 50 is pivotally suspended from the lower end of the ram in position to bear over the top lift of a heel. A set screw 51 provided with a hand wheel 52 is screwed into one side of the journal 47 in position to abut against a friction plate 53 in order to lock the ram 19 in any given position.
- Part way up the standard 46 there is provided a heel end abutment comprising a live rubber pad or block 54, carried by an internally threaded sleeve 55, which is slidable in a hollow boss 56 formed integrally in the press standard. An externally threaded spindle 57 is rotatably mounted

in the upper end of such boss and is equipped with a hand wheel 58 by means of which it may be turned so as to screw the sleeve 55 and its associated heel end abutment into any chosen position.

The ram 19, it will be noted, is located substantially directly above the pivot 30 of each press and each of these pivots is located equidistantly from the axis of rotation of the table 12, so that the rams describe a fixed circular path, above which the pressure applying piston rod 18 is directly located. Thus, rotation of the table is adapted successively to bring the ram of each press beneath such rod regardless of the relative position of such press with respect to its pivot 30. A detent for stopping the table with a press ram in registry with rod 18 is provided in the form of a pin 59, slidably mounted in the frame 10 and in a hollow boss 60 extending thereabove. The upper end of pin 59 is adapted successively to enter into each of a series of pin holes 61, located in the under side of a circular track 62 provided beneath table 12. These holes are so positioned with reference to the press as to register with the pin 59 at such time as their respective press rams 19 register with pressure rod 18. A spring 63 gives pin 59 a normal upward bias to rubbing contact with the under side of track 62 through means of a lever 64 having one end pivoted to the frame 10 and its other end joined by means of a suitable loose motion connection to the lower portion of pin 59. A treadle 65 and link 66 are provided for depressing pin 59 and releasing the table when desired.

Substantially directly beneath the pressure cylinder 16 is located a table support comprising a roller 67, mounted in standards 68, which in turn are mounted on and supported by the frame 10. This enables pressure to be applied to the press without exerting undue strains on the table bearing.

In operation, assuming the machine to be empty and the pressure piston 17 to be in its uppermost position, an operator stands facing the machine at the station directly below the pressure cylinder. He applies or activates cement between a lasted shoe and a heel which is to be affixed thereto and locates the shoe and heel on the jack pin 33. This insertion is facilitated by having the carriage 32 in its outermost position, the handle 42 being in the lowered position shown in Fig. 1 so that the heel is clear of the lower portion of the ram, as also shown in that figure. The plunger 43 of handle 42 is then depressed and the handle raised, sliding the carriage 32 back toward the standard 46 until the rear end of the heel is arrested by abutment 54 at which time the top lift of the heel will directly underlie seat 50 on the ram (Fig. 2), the abutment 54 being suitably adjusted to effect this relationship for the particular type of heel being used. The operator then moves treadle 23 so as to apply fluid pressure above the piston 17 and release the pressure therebelow, thus forcing the rod 18 downwardly into pressing relation with the ram 19 and forcing the latter against the heel, thus effecting a cushioned air pressing contact between the heel and shoe by the heel seat. When pressure thus has been applied, the set screw 51 is tightened sufficiently to hold the ram 19 in position after release from the pressure cylinder. The treadle 23 may then be moved so as to lift the piston 17 and rod 18 away from the press ram, at the same time expelling exhaust air through nozzle 26 so as to blow dust from a press

located at a station beyond the rasping or like equipment (not shown) which may suitably be located adjacent the table 12. The treadle 65 is then depressed, releasing the table and permitting it to be rotated either manually or by power means (not shown) until pin 59 engages in the next slot 61 on the under side of the table, at which time the loading and pressing operations are repeated until the entire machine is filled. 5 Subsequent operation of the machine will also involve unloading the press shoes, which will have set by the time they return to the loading station.

While the structure which has been described in detail above is a practical and preferred form 15 of the invention, it should be understood that it is merely illustrative of the principles involved, and that various changes may be made without departing from the disclosed and claimed invention. Thus, for example, the rotatable table 20 used for carrying the individual presses may, if desired, be replaced by any other suitable form of multiple press carrier, such as an elongate conveyor, a vertical wheel, or the like. Other suitable types of presses might also be used in conjunction with the disclosed air-cushioned pressure applying means, if desired, and the latter may 25 be located below the table if suitable connections to the presses are provided.

It will be seen that there has been provided an 30 apparatus which is well suited to fulfill its intended functions. Since certain changes may be made in the above construction and different embodiments of the invention could be made without departing from the scope thereof, it is 35 intended that all matter contained in the above description or shown in the accompanying drawing shall be interpreted as illustrative and not in a limiting sense.

It is also to be understood that the following 40 claims are intended to cover all of the generic and specific features of the invention herein described, and all statements of the scope of the invention which, as a matter of language, might be said to fall therebetween.

45 Having described my invention, what I claim as new and desire to secure by Letters Patent is:

1. A heel pressing machine comprising, in combination, a movable carrier, a plurality of heel presses carried thereby, each press having means for supporting a lasted shoe and a ram for pressing a heel thereagainst, a fixedly mounted fluid pressure cylinder, a piston in said cylinder having a downwardly projecting rod, said table being rotatable successively to present said rams beneath said rod, control means for admitting fluid into said cylinder to apply downward pressure to a ram located beneath said rod, and means for holding said ram in pressing relation against a heel.

60 2. A heel pressing machine comprising, in combination, a frame, a table rotatably mounted thereon, a plurality of heel presses carried by said table, each press having means for supporting a lasted shoe and a ram for pressing a heel thereagainst, a fluid pressure cylinder fixedly mounted above said table, a piston in said cylinder having a downwardly projecting rod, said table being rotatable successively to present said rams beneath said rod, control means for admitting fluid into said cylinder to apply downward pressure to a ram located beneath said rod, and means for holding said ram in pressing relation against a heel.

65 3. A heel pressing machine comprising, in

combination, a frame, a table rotatably mounted thereon, a plurality of heel presses carried by said table, each press having means for supporting a lasted shoe and a ram for pressing a heel thereagainst, an arm fixedly carried by said frame and extending above said table, a fluid pressure cylinder mounted on said arm, a piston in said cylinder having a downwardly projecting rod, said table being rotatable successively to present said rams beneath said rod, a support on said frame 10 beneath said cylinder engaging and supporting said table, control means for admitting fluid into said cylinder to apply downward pressure to a ram located beneath said rod, and means for holding said ram in pressing relation against a 15 heel.

4. A heel pressing machine comprising, in combination, a frame having a bearing thereon, a table rotatably mounted on said bearing, a plurality of heel presses carried by said table, each 20 press having means for supporting a lasted shoe and a ram for pressing a heel thereagainst, an arm fixedly carried by said frame and extending upwardly from said bearing, a fluid pressure cylinder mounted on said arm, a piston in said cylinder 25 having a downwardly projecting rod, said table being rotatable successively to present said rams beneath said rod, treadle operated valve means for admitting fluid into said cylinder to apply downward pressure to a ram located beneath said 30 rod, fluid conduits between said valve means and cylinder and passing through said bearing, and means for holding said ram in pressing relation against a heel.

5. A heel pressing machine comprising, in combination, a frame, a table rotatably mounted thereon, a plurality of heel presses carried by said table, air operated pressure cylinder means fixedly located with respect to said frame and adapted successively to apply pressure to said presses, and 40 means for utilizing air released from said pressure cylinder means to blow dust from the vicinity of one of said presses.

6. A heel pressing machine comprising, in combination, a frame, a table rotatably mounted thereon, a plurality of heel presses carried by said table, each press having means for supporting a lasted shoe and a ram for pressing a heel thereagainst, a fluid pressure cylinder fixedly mounted above said table, a piston in said cylinder having a downwardly projecting rod, said table being rotatable successively to present said rams beneath said rod, control means for admitting fluid into said cylinder to apply downward pressure to a ram located beneath said rod, means for utilizing fluid from said cylinder to blow dust from the vicinity of one of said presses, and means for holding said ram in pressing relation against a heel.

7. A heel pressing machine comprising, in combination, a frame having a hollow bearing thereon, a table mounted for horizontal rotation about said bearing, a plurality of heel presses carried by said table, each press having means for supporting a lasted shoe and a ram for pressing a heel thereagainst, a hollow column fixedly mounted on said bearing above said table, a cantilever arm extending outwardly from said column, a fluid pressure cylinder mounted on said arm, a piston in said cylinder having a downwardly projecting rod, 65 said table being rotatable successively to present said rams beneath said rod, treadle operated valve means for admitting fluid into said cylinder to apply downward pressure to a ram located beneath said rod, fluid conduits between said valve 70 and cylinder and passing through said bearing, and means for holding said ram in pressing relation against a heel.

75 8. A heel pressing machine comprising, in combination, a frame having a hollow bearing thereon, a table mounted for horizontal rotation about said bearing, a plurality of heel presses carried by said table, each press having means for supporting a lasted shoe and a ram for pressing a heel thereagainst, a hollow column fixedly mounted on said bearing above said table, a cantilever arm extending outwardly from said column, a fluid pressure cylinder mounted on said arm, a piston in said cylinder having a downwardly projecting rod, 75 said table being rotatable successively to present said rams beneath said rod, treadle operated valve means for admitting fluid into said cylinder to apply downward pressure to a ram located beneath said rod, fluid conduits between said valve and cylinder and passing through said bearing, and means for holding said ram in pressing relation against a heel.

- means and cylinder and passing through said bearing and column, and means for holding said ram in pressing relation against a heel.
8. A heel pressing machine comprising, in combination, a frame, a table horizontally rotatable thereon, a plurality of heel presses, each rotatably pivoted on said table, the pivots for said presses being equidistant from the axis of said table, means on each press for supporting a lasted shoe, a standard on each press, a ram slidably mounted in each standard and located for vertical movement over the pivot point of its respective press, a fluid operated pressure cylinder fixedly located above said table, a piston in said cylinder having a downwardly extending rod located directly above the path of movement of said rams, and control means for admitting fluid into said cylinder to apply downward pressure to a ram located beneath said rod.
9. A heel pressing machine comprising, in combination, a frame, a table horizontally rotatable thereon, a plurality of heel presses each rotatably pivoted on said table, the pivots for said presses being equidistant from the axis of said table, means on each press for supporting a lasted shoe, a standard on each press, a ram slidably mounted in each standard and located for vertical movement over the pivot point of its respective press, and a pressure applying means over said table including an element located directly over the path of movement of said rams and successively movable into pressing relation therewith.
10. A heel affixing machine comprising, in combination, a base, a table rotatable thereon, a plurality of heel presses carried by said table, each press comprising means for holding a shoe and means for engaging the top lift of a heel of said shoe, means located at a fixed station along said table for applying cushioned air pressure to said engaging means, and means for holding said engaging means in pressure applying relation against a heel.
11. In a heel pressing machine, the combination comprising a press base, a standard extending upwardly from said base, a ram slidably mounted on said standard, spring means normally holding said ram upwardly, shoe holding means movably mounted on said base to position a shoe heel beneath said ram, means for pushing said ram against such heel under pressure, and means for holding said ram in its pressure applying position.
12. In a heel pressing machine, the combination comprising a press base, a standard extending above said base, a ram slidably mounted on said standard, a last jack pin slidably mounted on said base, means for moving said pin with respect to said base to locate the heel of a shoe positioned thereon beneath said ram, and means for holding such pin in such position.
13. In a heel pressing machine, the combination comprising a press base, a standard extending above said base, a ram slidably mounted on said standard, a carriage slidably mounted on said base, a last jack pin on said carriage, a rack on said carriage, a pinion meshed with said rack, an operating handle for rotating said pinion, and means for locking said handle in a selected position.
14. In a heel pressing machine, the combination comprising a press base, a standard extending above said base, a ram slidably mounted on said standard, a carriage slidably mounted on said base, a jack pin holder adjustably mounted on said carriage, a rack on said carriage, a pinion meshed with said rack, a swingable operating handle for rotating said pinion, a locking dog carried by said handle, and a toothed plate carried by said press base in position to be engaged by said locking dog, and means for disengaging said dog and plate.
15. In a heel pressing machine, the combination comprising a press base, a standard extending upwardly from said base, a ram slidably mounted on said standard, shoe holding means movably mounted on said base to bring the heel of a shoe positioned thereon beneath said ram, abutment means carried by said standard in position to arrest movement of said shoe when its heel is positioned beneath said ram, means for pushing said ram against such heel under pressure, means for locking said holding means, and means for holding said ram in its pressure applying position.
16. Heel affixing apparatus comprising, in combination, a movable carrier, a plurality of heel presses mounted on said carrier, each press comprising means for holding a shoe and means for engaging the top lift of the heel of a shoe, means located at a fixed station along said carrier for applying cushioned air pressure to said engaging means, and means for holding said engaging means in pressure applying relation against a heel.
17. In a heel pressing machine, the combination comprising a press base, a standard extending above said base, a ram slidably mounted on said standard, shoe holding means movably mounted on said base to position the heel of a shoe held thereby opposite said ram, means for fixing said shoe holding means in such position, means for pushing said ram against such heel under pressure, and means for holding such ram in its pressure applying position.

WILLIAM C. CARD, JR.
